AIRCRAFT OR THE LIKE

Mike Tecton, 5101 45th St. NW,
Washington, D.C. 20016

Filed Sept. 3, 1965, Ser. No. 86,836

Term of patent 14 years

(Cl. D71—1)

FIG. 1

FIG. 2

FIG. 3

FIG. 1 is a side elevational view of an aircraft or the like, embodying my new design;

FIG. 2 is a top plan view thereof;

FIG. 3 is a front elevational view thereof.

The dominant features of my design reside in the portions shown in full lines.

I claim:

The ornamental design for an aircraft or the like, substantially as shown and described.
